ELECTRIC SWITCH WITH PERMANENT-MAGNET BLOWOUT FIELD

Ralph B. Immel, Williamsville, and Lawrence Pierce, Buffalo, N. Y., assignors to Westinghouse Electric Corporation, East Pittsburgh, Pa., a corporation of Pennsylvania

Application July 7, 1950, Serial No. 172,522

3 Claims. (Cl. 200—147)

1

Our invention relates to manually or automatically operated electric switches and more particularly to switch contact devices with permanent magnets to provide an arc blowout field.

Known devices of this kind have, for each interrupting gap, a single permanent magnet mounted stationarily in the vicinity of the stationary switch contacts. Unless the magnet is very large and thus occupies considerable space in excess of that needed by the contact device proper, the blowout effect and, accordingly, the interrupting rating of these known devices are rather limited.

It is an object of our invention to materially increase the interrupting rating of switching devices of the above-mentioned kind by providing a blowout field of higher intensity or effectiveness with the aid of permanent magnets of simple design and little or no space requirements in excess of the space needed for the switching devices proper. Another, related object of the invention is to provide a permanent-magnet blowout unit that is generally suitable for direct-current contact devices and can readily be substituted for devices without blowout by mounting it in the same place and space.

To achieve these objects, and in accordance with the invention, we mount a permanent magnet behind the stationary contact member of the switching device and mount another permanent magnet on and behind the appertaining movable contact member in sufficiently close magnetic relation to the stationary magnet to jointly produce a blowout field not only of higher intensity but also of a more favorable orientation than otherwise obtainable, these and other features of the invention being apparent from the embodiment exemplified on the drawing and described in the following:

In the drawing, Fig. 1 is a part-sectional side view of a switching device according to the invention in closed condition; Fig. 2 is a similar view but shows the device in open condition; Fig. 3 is a perspective view of the same device during opening performance; and Fig. 4 is an explanatory illustration showing a section through the contact members and permanent magnets in a relative position corresponding to Fig. 3 and schematically representing the blowout field by lines of force.

The drawing demonstrates the invention in its application to a manually operated cam-type master or control switch although it should be understood that the invention is applicable to all types of switching devices involving a mov-

2

ing contact and a stationary contact in which the arc drawn between the contacts, during separation of the movable contact from the stationary contact, is to be extinguished by means of a permanent magnet field.

The illustrated switching device has an insulating panel or base 1. A stationary contact member 2 is mounted on the base 1 by a threaded stud 3 which serves also as an electrical terminal. 10 Another stationary contact member 4 is positioned beneath assembly 2 and secured to base 1 by a stud 5 which serves also as an electrical terminal.

The contact members 2 and 4 carry respective contact buttons 6 and 7 which are engageable with respective contact buttons 8 and 9 of a movable contact bridge 10. The contact buttons consist preferably of good electrical conducting material, for example, silver. The bridge 10 is resiliently secured to an arm 11 which is pivoted at 12 in a support 13. Support 13 is firmly attached to base 1 by a screw 14 and is indexed by means of a dowel pin 15 engaging a hole in the base 1. The resilient mounting for bridge 10 includes a pin 17 which is fitted through a hole in arm 11 and passes through a clearance hole of bridge 10. Bridge 10 can slide along pin 17 and is biased toward a supporting surface of arm 11 by a compression spring 18. Spring 18 is seated on pin 17, between the bridge 10 and a washer 19 at the extremity of pin 17.

The movable arm 11 is biased in a clockwise direction, as viewed in Fig. 1, by a compression spring 20, which is disposed between a shoulder 21 on the movable arm 11 and seats against the bottom of a hole 22 in the supporting member 13. Spring 20 tends to force the movable contact assembly against the stationary contact assemblies under compression of the weaker spring 18.

40 In this application, the movable arm 11 is cam actuated and to this end is provided with a roller 23 which is pivotally mounted at a point displaced from the pivot 12. Roller 23 is engageable by a control cam 24. Rotation of the cam from the position shown in Fig. 1 to a position in which it engages the roller 23 results in counterclockwise rotation of the movable member to the switch-opening position shown in Fig. 2.

45 The stationary contact member 2 is U-shaped. A permanent magnet 25 is secured between the U-legs of the member. Magnet 25 is also U-shaped and has its north and south pole ends, marked N and S in Fig. 4, abut against the one leg of member 2 that carries the contact button

6. The movable bridge member 10 has a U-shaped end portion near contact button 10. Another permanent magnet 26 is secured between the legs of this end portion. Magnet 26 is also U-shaped and has its pole ends, marked N and S in Fig. 4, in abutment with the one leg of bridge 10 that carries the adjacent contact button 8.

The two magnets 25 and 26 consist of a material of high coercive force and high remanence, for instance, of a sintered aluminum-nickel-cobalt alloy, although other permanent magnets of highly magnetic material are also suitable. The material of the stationary contact member 2 and the bridge 10 is nonmagnetic, and all other parts of the stationary and movable contact assemblies are preferably also nonmagnetic.

Magnet 26 is held in place by a set screw shown at 27 in Figs. 1 and 3. The set screw engages a small dowel hole of the magnet. Magnet 25 is similarly fastened to member 2 by a chamfer of screw 3 which enters into a small dowel recess of the magnet. Other ways of fastening the magnets, of course, may be used, but the one just mentioned is simple and prevents damaging the magnets mechanically or magnetically especially if magnets as brittle as aluminum-nickel-cobalt type magnets are used.

The arrangement or poling of the two permanent magnets is such that respective poles of like polarity lie at the same side of the switching device as is apparent from Fig. 4. Poling the magnets in this manner concentrates the field at the place where the contacts separate and results in lines of force approximately parallel to the contact surfaces and perpendicular to the arc. The relationship of current flow in the arc, magnetic field direction, and arc movement then obtaining is elucidated by arrows in Fig. 3 and Fig. 4. In Fig. 3 the arrows C indicate the direction of current flow under given conditions, and the arrow marked "Current" in the top portion and below the illustration of structure in Fig. 3 denotes the corresponding direction of current flow in the arc. Arrows F in Figs. 3 and 4 denote the prevailing force line directions of the stationary magnetic field component while arrows F_m in both figures denote the corresponding prevailing directions for the movable magnet field. The resultant field direction is denoted by the arrow marked "Field" at the bottom of Fig. 3 for the indicated north (N) and south (S) polarity arrangement of the magnets. The direction of the arc movement is denoted in Fig. 3 by the arrows marked "Arc."

As thus made apparent in Figs. 3 and 4, the resultant magnetic flux is concentrated in one desirable path perpendicular to the arc. It may be mentioned that this condition and the resulting improvement in arc extinction and interrupting capacity is obtained only if opposite poles of the respective magnets are of like polarity. If these poles are of the opposite polarity, the flux is concentrated not in one desirable path, but in two less desirable paths parallel to the arc, and the result, as tests have shown, is no better than when one magnet only is mounted on the stationary contact assembly.

Devices according to the invention are especially advantageous for switches that may involve a slow-operating contact separation. For instance, aside from manual switches, the invention is particularly well suited as a limit switch for motor operated rheostats. In such applications, the rheostat mechanism may open the contact very slowly so that the contact surfaces

of the customary switches may become damaged by burning before the arc is extinguished, while such defects are greatly minimized or prevented by the invention. However, fast-operating switching devices as well as switching apparatus other than herein specifically mentioned also benefit from the invention in permitting a higher interrupting rating; and it will also be obvious to those skilled in the art that changes and modifications in design, arrangement and structural details can readily be made without departure from the objects and essential features of the invention.

We claim as our invention:

- 15 1. In an electric switching device, the combination including, a base of insulating material, a contact member stationarily mounted on the base; a stationary permanent magnet mounted substantially behind the stationary contact member and having respective north and south poles directed away from the base, a movable contact member having a U-shaped portion with two parallel legs and being engageable at the outside of one of said legs with said stationary contact member, a movable permanent magnet mounted on the U-shaped portion between the two legs of the U and having respective north and south poles directed toward the stationary permanent magnet, said two magnets having respective poles of like polarities substantially facing each other.
- 20 2. In an electric switching device, the combination including, a base of insulating material, a stationary U-shaped member mounted on the base with one leg against the base and the other leg disposed away from the base, a stationary contact fixed to the outer surface of the said other leg, a one piece permanent magnet mounted in the bight of the U and having its poles disposed substantially at the respective sides of the stationary contact, a movable U-shaped member disposed substantially opposite the stationary U-shaped member, a movable contact fixed to the outer surface of the leg of the movable U-shaped member in relation for engagement with the stationary contact, a one piece permanent magnet mounted in the bight of the U of the movable U-shaped member and having its poles disposed substantially at the respective sides of the movable contact, said two magnets having respective poles of like polarities substantially facing each other.
- 25 3. In an electric switching device, the combination including, a base of insulating material, a U-shaped member mounted on the base with one leg of the U against the base and the other facing outwardly, or away, from the base, an upper stationary contact mounted on the outer surface of the outer leg of the U, a lower stationary contact mounted on the base substantially in the plane of the upper stationary contact, an arm pivoted below the lower stationary contact, a contact bridging member, having an upper contact and a lower contact, for bridging the stationary contacts, said contact bridging member being mounted on the arm whereby the upper contacts are disposed a greater distance from each other when the arm moves the contact bridging member away from the stationary contacts, a one piece U-shaped permanent magnet mounted in the U-shaped member so that the poles thereof are substantially at the sides of the upper stationary contact, a one piece U-shaped permanent magnet similarly mounted with respect to the upper movable contacts, said two magnets having respective poles of like

- 30 4. In an electric switching device, the combination including, a base of insulating material, a U-shaped member mounted on the base with one leg of the U against the base and the other facing outwardly, or away, from the base, an upper stationary contact mounted on the outer surface of the outer leg of the U, a lower stationary contact mounted on the base substantially in the plane of the upper stationary contact, an arm pivoted below the lower stationary contact, a contact bridging member, having an upper contact and a lower contact, for bridging the stationary contacts, said contact bridging member being mounted on the arm whereby the upper contacts are disposed a greater distance from each other when the arm moves the contact bridging member away from the stationary contacts, a one piece U-shaped permanent magnet mounted in the U-shaped member so that the poles thereof are substantially at the sides of the upper stationary contact, a one piece U-shaped permanent magnet similarly mounted with respect to the upper movable contacts, said two magnets having respective poles of like
- 35 5. In an electric switching device, the combination including, a base of insulating material, a stationary U-shaped member mounted on the base with one leg against the base and the other leg disposed away from the base, a stationary contact fixed to the outer surface of the said other leg, a one piece permanent magnet mounted in the bight of the U and having its poles disposed substantially at the respective sides of the stationary contact, a movable U-shaped member disposed substantially opposite the stationary U-shaped member, a movable contact fixed to the outer surface of the leg of the movable U-shaped member in relation for engagement with the stationary contact, a one piece permanent magnet mounted in the bight of the U of the movable U-shaped member and having its poles disposed substantially at the respective sides of the movable contact, said two magnets having respective poles of like polarities substantially facing each other.
- 40 6. In an electric switching device, the combination including, a base of insulating material, a stationary U-shaped member mounted on the base with one leg against the base and the other leg disposed away from the base, a stationary contact fixed to the outer surface of the said other leg, a one piece permanent magnet mounted in the bight of the U and having its poles disposed substantially at the respective sides of the stationary contact, a movable U-shaped member disposed substantially opposite the stationary U-shaped member, a movable contact fixed to the outer surface of the leg of the movable U-shaped member in relation for engagement with the stationary contact, a one piece permanent magnet mounted in the bight of the U of the movable U-shaped member and having its poles disposed substantially at the respective sides of the movable contact, said two magnets having respective poles of like polarities substantially facing each other.
- 45 7. In an electric switching device, the combination including, a base of insulating material, a U-shaped member mounted on the base with one leg of the U against the base and the other facing outwardly, or away, from the base, an upper stationary contact mounted on the outer surface of the outer leg of the U, a lower stationary contact mounted on the base substantially in the plane of the upper stationary contact, an arm pivoted below the lower stationary contact, a contact bridging member, having an upper contact and a lower contact, for bridging the stationary contacts, said contact bridging member being mounted on the arm whereby the upper contacts are disposed a greater distance from each other when the arm moves the contact bridging member away from the stationary contacts, a one piece U-shaped permanent magnet mounted in the U-shaped member so that the poles thereof are substantially at the sides of the upper stationary contact, a one piece U-shaped permanent magnet similarly mounted with respect to the upper movable contacts, said two magnets having respective poles of like
- 50 8. In an electric switching device, the combination including, a base of insulating material, a stationary U-shaped member mounted on the base with one leg against the base and the other leg disposed away from the base, a stationary contact fixed to the outer surface of the said other leg, a one piece permanent magnet mounted in the bight of the U and having its poles disposed substantially at the respective sides of the stationary contact, a movable U-shaped member disposed substantially opposite the stationary U-shaped member, a movable contact fixed to the outer surface of the leg of the movable U-shaped member in relation for engagement with the stationary contact, a one piece permanent magnet mounted in the bight of the U of the movable U-shaped member and having its poles disposed substantially at the respective sides of the movable contact, said two magnets having respective poles of like polarities substantially facing each other.
- 55 9. In an electric switching device, the combination including, a base of insulating material, a U-shaped member mounted on the base with one leg of the U against the base and the other facing outwardly, or away, from the base, an upper stationary contact mounted on the outer surface of the outer leg of the U, a lower stationary contact mounted on the base substantially in the plane of the upper stationary contact, an arm pivoted below the lower stationary contact, a contact bridging member, having an upper contact and a lower contact, for bridging the stationary contacts, said contact bridging member being mounted on the arm whereby the upper contacts are disposed a greater distance from each other when the arm moves the contact bridging member away from the stationary contacts, a one piece U-shaped permanent magnet mounted in the U-shaped member so that the poles thereof are substantially at the sides of the upper stationary contact, a one piece U-shaped permanent magnet similarly mounted with respect to the upper movable contacts, said two magnets having respective poles of like
- 60 10. In an electric switching device, the combination including, a base of insulating material, a stationary U-shaped member mounted on the base with one leg against the base and the other leg disposed away from the base, a stationary contact fixed to the outer surface of the said other leg, a one piece permanent magnet mounted in the bight of the U and having its poles disposed substantially at the respective sides of the stationary contact, a movable U-shaped member disposed substantially opposite the stationary U-shaped member, a movable contact fixed to the outer surface of the leg of the movable U-shaped member in relation for engagement with the stationary contact, a one piece permanent magnet mounted in the bight of the U of the movable U-shaped member and having its poles disposed substantially at the respective sides of the movable contact, said two magnets having respective poles of like polarities substantially facing each other.
- 65 11. In an electric switching device, the combination including, a base of insulating material, a stationary U-shaped member mounted on the base with one leg against the base and the other leg disposed away from the base, a stationary contact fixed to the outer surface of the said other leg, a one piece permanent magnet mounted in the bight of the U and having its poles disposed substantially at the respective sides of the stationary contact, a movable U-shaped member disposed substantially opposite the stationary U-shaped member, a movable contact fixed to the outer surface of the leg of the movable U-shaped member in relation for engagement with the stationary contact, a one piece permanent magnet mounted in the bight of the U of the movable U-shaped member and having its poles disposed substantially at the respective sides of the movable contact, said two magnets having respective poles of like polarities substantially facing each other.
- 70 12. In an electric switching device, the combination including, a base of insulating material, a stationary U-shaped member mounted on the base with one leg against the base and the other leg disposed away from the base, a stationary contact fixed to the outer surface of the said other leg, a one piece permanent magnet mounted in the bight of the U and having its poles disposed substantially at the respective sides of the stationary contact, a movable U-shaped member disposed substantially opposite the stationary U-shaped member, a movable contact fixed to the outer surface of the leg of the movable U-shaped member in relation for engagement with the stationary contact, a one piece permanent magnet mounted in the bight of the U of the movable U-shaped member and having its poles disposed substantially at the respective sides of the movable contact, said two magnets having respective poles of like
- 75 13. In an electric switching device, the combination including, a base of insulating material, a stationary U-shaped member mounted on the base with one leg against the base and the other leg disposed away from the base, a stationary contact fixed to the outer surface of the said other leg, a one piece permanent magnet mounted in the bight of the U and having its poles disposed substantially at the respective sides of the stationary contact, a movable U-shaped member disposed substantially opposite the stationary U-shaped member, a movable contact fixed to the outer surface of the leg of the movable U-shaped member in relation for engagement with the stationary contact, a one piece permanent magnet mounted in the bight of the U of the movable U-shaped member and having its poles disposed substantially at the respective sides of the movable contact, said two magnets having respective poles of like

polarities disposed to substantially face each other.
